UNITED STATES PATENT OFFICE.

HENRY HERMAN WESTINGHOUSE, OF PITTSBURG, PENNSYLVANIA.

QUICK-ACTION TRIPLE VALVE.

SPECIFICATION forming part of Letters Patent No. 518,929, dated April 24, 1894.

Application filed December 14, 1893. Serial No. 493,647. (No model.)

To all whom it may concern:

Be it known that I, HENRY HERMAN WESTINGHOUSE, a citizen of the United States, residing at Pittsburg, in the county of Allegheny and State of Pennsylvania, have invented or discovered a certain new and useful Improvement in Quick-Action Triple Valves, of which improvement the following is a specification.

The object of my invention is to provide a novel and improved quick action appliance for automatic fluid pressure brake systems; and to this end it consists, generally stated, in improved means by which the release of fluid under pressure from the train pipe is effected and controlled by the movement of the triple valve piston.

The improvement claimed is hereinafter fully set forth.

In the accompanying drawings: Figure 1 is a central section through a quick action triple valve illustrating an embodiment of my invention, the parts being shown in their normal or release positions; Fig. 2, a similar section showing the parts in the positions which they occupy in making an emergency, or quick, application of the brakes; Fig. 3, a view showing the face of the slide of the triple valve; and, Fig. 4, a plan view of the seat of the slide valve of the triple valve.

In the drawings, I have illustrated my invention in connection with a triple valve of the Westinghouse type, but it is not limited to such specific form of quick action mechanism, nor to any other particular style or form of triple valve device. The casing, 1, of the triple valve is connected with the train pipe, or a branch therefrom, by means of the screw threaded nipple 2, and fluid from the train pipe flows through the passages 3, 4, 5, and passages 6, into the piston chamber 7, where it acts on the movable abutment, or piston, 8, and moves it to the right, to the extremity of its stroke, as shown in Fig. 1. The fluid from the train pipe then passes

45 through the feed groove, 9, around the piston, and into the chamber 10 which is in open communication with the auxiliary reservoir. The slide valve, 11, is loosely fitted between the shoulders formed on the stem 12, of the piston 8, and is provided with ports 13 and 14, for admitting fluid, through the port 19 in the valve seat, from the auxiliary reservoir to the

brake cylinder, in making service and emergency applications of the brakes, and with an exhaust recess or cavity, 15, for exhausting 55 fluid from the brake cylinder to the atmosphere in releasing the brakes.

In addition to the ports or passages already mentioned, a cavity or recess 20 is formed in the face of the slide valve 11, by means of 60 which it is adapted to effect the operation of the quick action valve device for quickly releasing the fluid under pressure from the train pipe, as presently to be described.

When the train pipe is charged, fluid under 65 pressure fills the passage 21 and communicating passage 22, and, acting on the under side of the check valve 23, lifts it from its seat, and flows into the chamber 24, where it acts on the back of the quick action valve 25, and 70 tends to hold it to its seat. The check valve, 23, and the quick action valve, 25, are both normally seated, being held to their seats by the spring 26, which is located in the tubular stem 27 of the check valve, and bears, at one 75 end, against the bottom of the tubular stem, and, at the other end, against the stem, 28, of the quick action valve. The check valve 23 closes when the pressure in the chamber 24 is nearly equalized with the train pipe pressure. 80 The quick action valve, 25, controls a passage 29, leading from the chamber 24 into a chamber, 30, in which is located a supplementary movable abutment or piston, 31, having a tubular stem 32 which fits over a guide 85 stem 33 projecting from the quick action valve. The stem 32, of the piston 31, is fitted to move in guides 34, and, as shown, is not positively connected with the stem 33 of the quick action valve. If preferred, however, 90 the quick action valve and the piston may be positively connected by a single stem, or the connection between them may be otherwise varied; the essential feature of the construction being that a sufficient movement of 95 the piston from its normal position shall open the quick action valve.

A passage 16 leads from the passage 4, which is normally in open communication with the train pipe, to a port 17 in the seat, 18, of the slide valve 11, and a port or passage 35, in the valve seat, communicates with one end of the chamber 30, above the piston 31. The ports 17 and 35 are disconnected, and the

port 17 is closed by the face of the slide valve when the slide valve is in its normal, or release, position, or when it is in the service position, that is, the position in which the 5 port 13 in the slide valve registers with the brake cylinder port 19. When, however, a sufficiently great and rapid reduction of train pipe pressure is effected to produce an emergency application of the brakes, the slide 10 valve 11 is moved by the piston 8 to the limit of its stroke to the left, as shown in Fig. 2, and the recess or cavity 20, in the slide valve, connects the ports 17 and 35 in the valve seat. Fluid under pressure from the train pipe then 15 flows through the passage 16, cavity 20, and port or passage 35, into the chamber 30 above the piston 31, and, acting on the piston 31, forces it down on the stem 33 and unseats the quick action valve 25. When the quick action 20 valve is unseated, the fluid under pressure in the chamber 24 escapes into the chamber 30, and, through the passage 36, into the brake cylinder. The release of pressure above the check valve 23 permits the fluid under pressure 25 in the train pipe to lift said check valve, and, the quick action valve, 25, being open, the fluid from the train pipe flows through the passage 22, chamber 24, passage 29, chamber 30, and passage 36, to the brake cylinder. 30 When, or slightly before, the train pipe pressure equals with the pressure in the brake cylinder, the check valve, 23, returns to its seat, and prevents a back flow of fluid from the brake cylinder to the train pipe. At the same 35 time that the ports 17 and 35 are connected, by the cavity 20, the port 14 in the slide valve registers with the port 19 in the valve seat, and fluid under pressure flows from the auxiliary reservoir through the ports 14 and 19, 40 and passages 37 and 36, into the brake cylinder. When the train pipe is again charged, for the purpose of releasing the brakes, the piston 8 and the slide valve 11 are returned to the positions shown in Fig. 1. Communication 45 between the auxiliary reservoir and the brake cylinder is then cut off by the closing of the ports 13 and 14 in the valve; communication between the brake cylinder and the atmosphere is opened by connecting the 50 port 19 with the exhaust port 38, through the cavity 15 in the valve; and the port 17 in the valve seat is disconnected from the port or passage 35, by being covered by the face of the slide valve, communication being thereby 55 cut off between the passage 16 and the chamber 30. The fluid admitted to the chamber 30, above the piston 31, is permitted to escape either around the piston, which may be loosely fitted for that purpose, or through one 60 or more openings through the piston, or through a groove formed in the edge of the piston or in the wall of the piston chamber. Such openings or passages must not, however, be so large as to interfere with or prevent the 65 prompt action, on the piston, of the fluid admitted above the piston for the purpose of opening the quick action valve.

If preferred, a diaphragm may be employed instead of the piston 31, and the fluid released from the train pipe may be permitted 70 to escape to the atmosphere or to a reservoir or chamber, or to a second brake cylinder.

While I have shown a slide valve adapted to operate both as a supply and release valve, for admitting fluid from the auxiliary reservoir to the brake cylinder and releasing it from the brake cylinder to the atmosphere, as shown in Letters Patent No. 360,070, granted and issued to George Westinghouse, Jr., March 29, 1887, my invention is not limited 80 in its application to the employment of such specific construction. The slide valve, in addition to its function in connection with my invention, may operate merely as an exhaust valve, for releasing fluid from the brake cylinder to the atmosphere; or, if preferred, a separate valve of any form operated by the triple valve piston, may be employed in connection with a triple valve of either the slide or of the puppet valve type. 90

I claim as my invention and desire to secure by Letters Patent—

1. In an automatic fluid pressure brake system, the combination with a movable abutment and a release valve controlling a passage for the release of fluid under pressure from the train pipe, of a main valve of a triple valve, controlling the admission of fluid from the train pipe to the movable abutment, for opening the release valve, substantially as set 100 forth.

2. In an automatic fluid pressure brake system, the combination, with a release valve controlling a passage from the train pipe, of a movable abutment having normally an equilibrium of fluid pressures on its opposite sides, a passage through which fluid may be admitted from the train pipe to the abutment, and a valve operated by the triple valve piston for admitting fluid under pressure from the 110 train pipe to the movable abutment for opening the release valve, substantially as set 115 forth.

3. In an automatic fluid pressure brake system, the combination, with a release valve 115 controlling a passage from the train pipe, of a movable abutment exposed on one side to brake cylinder pressure and a valve operated by the piston of a triple valve for admitting train pipe pressure to the other side of the 120 movable abutment, substantially as set forth.

4. In an automatic fluid pressure brake system, the combination, with a triple valve, of a release valve controlling a passage from the train pipe, a supplementary movable 125 abutment having, normally, an equilibrium of fluid pressures on its opposite sides, and a valve operated by the triple valve piston and adapted to admit fluid under pressure 130 from the train pipe to the supplementary movable abutment when the triple valve piston is in the emergency position, substantially as set forth.

5. In an automatic fluid pressure brake sys-

tem, the combination, with a triple valve, of a release valve controlling a passage for the release of fluid under pressure from the train pipe, a movable abutment, for operating the release valve, which is fitted in a chamber normally disconnected from the train pipe, and a valve, operated by the movement of the triple valve piston, for admitting fluid under

pressure from the train pipe to the movable abutment, substantially as set forth.

In testimony whereof I have hereunto set my hand.

HENRY HERMAN WESTINGHOUSE.
